UNITED STATES PATENT OFFICE.

ANDREW TIIKKAINEN, OF VIRGINIA, MINNESOTA, ASSIGNOR OF ONE-HALF TO
HENRY V. NURMI, OF VIRGINIA, MINNESOTA.

OIL-CAN AND CUP HOLDER.

1,377,160.

Specification of Letters Patent.

Patented May 3, 1921.

Application filed May 17, 1920. Serial No. 381,897.

To all whom it may concern:

Be it known that I, ANDREW TIIKKAINEN, a citizen of the Republic of Russia, residing at Virginia, in the county of St. Louis and 5 State of Minnesota, have invented certain new and useful Improvements in an Oil-Can and Cup Holder, of which the following is a specification.

This invention relates to an oil can and 10 cup holder and has for its principal object the provision of simple and efficient means for supporting an oil can or cup in a moving vehicle so that the oil can or cup will be firmly held from jarring loose from the 15 support no matter what position the moving vehicle may take. The holder is especially adapted to be used in such vehicles as railroad trains, boats, aeroplanes, and automobiles for holding cans, drinking cups and 20 the like and furthermore these containers may be of various sizes as the holder is yieldable for the accommodation of receptacles of different sizes.

Another object of this invention resides 25 in the production of a device of this nature which may be manufactured at a low cost and yet be durable and well able to withstand the rough usages to which they may be subjected.

30 Another object of the invention is to produce a device of this nature which may be bent so as to be easily attached to a vertical or a horizontal support.

A still further object of the invention resides 35 in the production of a movable member in combination with a stationary member, said movable member constructed so that it may be moved so that the device will accommodate vessels of different sizes.

40 With these and other objects in view this invention consists of the certain novel combination, arrangement, and construction of parts as will be hereinafter more fully described and especially pointed out in the 45 appended claims.

In the drawing:

Figure 1 is a longitudinal section through my invention,

50 Fig. 2 is a bottom plan view thereof, and Fig. 3 is a rear elevation thereof.

By referring to the accompanying drawings by numerals it will be seen that 1 designates the stationary member having the rectangular shaped body portion and

having its edges 2 bent over upon the body 55 portion so as to form a guideway into which is adapted to slide the movable member 3. The stationary member 1 has its bent portions 2 provided with the stop 4 at one end while the other end is bent at right angles 60 to the body portion as shown by the numeral 5. Upon the rear edge of the stationary portion 1 there is a provided the bracket plate 6 shown especially in Figs. 1 and 3 of the drawing. This bracket plate 6 is provided 65 with apertures 7 so that the same may be fixedly attached to a support by means of screws and it will be noted that this extension 6 or bracket plate may be bent easily at right angles to the stationary member 1 or 70 so as to extend in alinement therewith whereby the same may be attached to a vertical or a horizontal support. It should also be noted that when the device is attached to a vertical support as indicated in Fig. 1 by 75 dotted lines that the bent portions 5 will bear against the vertical support thus relieving the bracket of such strain as would have a tendency to bend the device so that the bracket plate 6 would be in alinement 80 with the stationary member 1. This is also true when the device is attached to a horizontal shelf as these bent members 5 will bear against the outer edge of the shelf.

The movable member 3 is provided adjacent its side edges with the struck-up portion 8 so as to engage the stops 4 when the device is pulled out to its full length for accommodating a rather large oil can or container thus preventing the two members 90 from being accidentally pulled apart. On the forward edge of the movable member 3 I have provided the finger engaging lip 9 so that the operator may grasp the movable member for sliding same outwardly. A compression spring 10 is attached at one end to the lip 9 and its other end is attached to the perforated ear 11 struck from the bottom edge of the bracket 6. Struck upwardly from the rear portions of the stationary 100 member 1 I have provided the lugs 12 which are bent outwardly at their top portions and have the rubber sockets 13 surrounding their body portions. A similar lug 14 is struck up from the outer edge of the movable member 105 3 and is also provided with a rubber socket 15. This lug also acts as a stop to prevent the inward movement of the movable plate.

These lugs 12 and 14 are adapted to engage the bottom of the oil can or other container as is shown in Fig. 1 of the drawing.

It is thought that the operation of my device will be clearly understood from the above description from which it will be seen that the movable plate is pulled outwardly and the oil can placed on top of the stationary plate 1 as indicated in dotted lines in Fig. 1 and the movable plate will then be released so that the can will be firmly held between the lugs 12 and 14 by the action of the compression spring 10. Although I have described the preferred embodiment of my invention it will be readily seen that numerous minor changes may be made in the construction thereof without departing from the spirit of my invention and I therefore reserve the right to make such changes in arrangement, combination, and construction of parts as will fall within the scope of the appended claims.

Having thus described my invention what I claim as new is:—

1. A device of the class described comprising a stationary member and a movable member, the side edges of said stationary member being bent over upon the body portion thereof so as to form a guideway for said movable member, stops formed on the forward end of said bent portion, lugs struck from out of said movable member so as to engage said stops when said members are in an extended position, and means for normally holding said members in a closed position.

2. A device of the class described comprising a stationary member and a movable

member, a pair of lugs struck upwardly from said stationary member, a lug struck upwardly from said movable member, a bracket plate extending from the rear edge of said stationary plate, a finger engaging lip provided upon the forward edge of said movable member, bent extensions provided upon the side edges of said stationary member so as to form guideways for said movable member, stops formed on said bent portion, struck out lips provided upon said movable members so as to engage said stop members when the device is in an extended position, and means for normally holding said device in a closed position.

3. A device of the class described comprising a stationary member and a movable member, bent extensions provided on the side edges of said stationary member for forming guideways for said movable member, a bracket plate extending from the rear edge of said stationary member, a finger engaging lip extending from the forward end of said movable member, stops provided on said bent portion, struck out lips provided on said movable members so as to engage said stop member when the device is in an extended position, means provided on said members for grasping an oil can, and means for normally holding said members in a closed position.

In testimony whereof I affix my signature in presence of two witnesses.

ANDREW TIIKKAINEN.
